UNITED STATES PATENT OFFICE.

HENRY CLAY GIBSON, OF LITTLE ROCK, ARKANSAS.

MANICURE-STICK.

1,112,207.

Specification of Letters Patent. Patented Sept. 29, 1914.

Application filed March 21, 1914. Serial No. 826,331.

To all whom it may concern:

Be it known that I, HENRY CLAY GIBSON, a citizen of the United States, and resident of Little Rock, in the county of Pulaski and State of Arkansas, have invented a new and useful Improvement in Manicure-Sticks, of which the following is a specification.

My invention is an improvement in manicure sticks, and has for its object to provide a device of the character specified, wherein a support is provided for holding an abrading device, as for instance, a file for abrading the finger nails in such manner that while the abrading surface is held in a manner to be easily accessible, a guide is furnished for guiding the nail during the abrading operation, and for limiting the extent of the nail which may be abraded.

In the drawings:—Figure 1 is a top plan view of the improved stick, Fig. 2 is a section on the line 2—2 of Fig. 1, and Fig. 3 is an enlarged transverse section.

The present embodiment of the invention comprises a support 1 of orange wood or other suitable material, provided at one end preferably with a point 2, for cleaning between the nail and the ends of the finger, and the other end is beveled as shown at 3 and rounded to provide means for pushing back the skin at the base of the nail. The stick as shown, is the usual form of manicure or orange wood stick, so far as concerns its ends. A nail file 4 is supported by the stick, the stick having a transverse longitudinally extending slot 5, intermediate its upper and lower faces into which the file is inserted. The stick is also reduced laterally at each side edge at the file as indicated at 6, to expose the central portion of the file. The file is of the usual shape, being of greatest diameter at its center and gradually decreasing in diameter toward its ends, and the file in the present instance, is held in place by rivets 7, the rivets being passed through the stick 1 and through the file near the ends thereof. At

the ends of the file, the side edges thereof gradually merge into the same line with the side edges of the stick as shown in Fig. 1, so that the stick, as a whole, is of greatest width at its center, gradually decreasing in width toward each end.

This manner of mounting the file provides for a portion of the file at each side of the stick which extends beyond the adjacent side edge of the stick, and it will be evident that either face of the extended portion at either side of the stick is accessible for engagement by the nail to abrade the same. Furthermore the adjacent side edges of the stick provide for a guide at each side during the movement of the nail or the stick, to prevent the nail from slipping off the file. When the stick is used with the end of the finger or thumb bearing against one face of the stick and with the finger nail extending into contact with the cutting surface of the file, a guide is provided for limiting the amount of nail removed.

The stick preferably is the usual orange wood stick, and the thickness of that portion of the stick at each face of the file may be of any desired degree, depending upon the amount of nail that it is desired to remove.

I claim:

A manicure stick comprising a plate of suitable material longitudinally slotted intermediate its ends, the plane of the slot being approximately parallel with the side faces of the plate, a strip held in the slot, the opposite faces of the strip being abrasive, said bar being of less width intermediate its ends and gradually increasing in width toward its ends to expose a portion of the strip at each side of the bar from near one end of the bar to near the other, the side edges of the strip at the ends thereof being flush with the side edges of the bar.

HENRY CLAY GIBSON.
